TREATMENT OF HYDROCARBONS

Harold V. Atwell, White Plains, N. Y., assignor to
Process Management Company, Incorporated,
New York, N. Y., a corporation of Delaware

Application April 2, 1938, Serial No. 199,560

1 Claim. (Cl. 196—10)

This invention relates to treatment of hydrocarbon fluids to produce low boiling hydrocarbons suitable as motor fuels.

According to this invention an oil, which does not decompose to form substantial quantities of coke or tar and which can be substantially completely vaporized, is mixed and burned in a gas generator with a limited amount of air, preferably preheated, and the oil undergoes partial combustion. As a result of the partial combustion, the temperature of the oil is raised to a relatively high temperature and the unburned oil is vaporized and cracked to produce a mixture of products containing a relatively large proportion of unsaturated or olefin hydrocarbon gases, which may be converted into higher boiling hydrocarbons suitable as motor fuel. This step in the process is carried out in such manner to yield the largest amount of unsaturated hydrocarbons possible. The hot products in the generator also contain some saturated hydrocarbon gases, products of combustion, hydrogen, nitrogen, etc.

The converted hydrocarbon gases and other gaseous products from the gas generator are passed to a coking or suitable conversion chamber wherein they are mixed with a heavy oil such as a heavy residual oil or the like and the heavy oil is raised to a conversion temperature and is converted into vapors and gases and coke or a heavy residual oil. During this conversion operation due to the relatively high temperatures, additional quantities of olefinic or unsaturated hydrocarbon gases are produced from the heavy oil being converted by heat derived from the products of the gas generator. Using cheap and dirty oils in the coking or conversion operation I can produce relatively large amounts of unsaturated hydrocarbons which can be further heated and converted into valuable gasoline constituents of high antiknock value. The unsaturated hydrocarbons formed during the coking operation are added to the unsaturated hydrocarbons formed during the partial combustion of the fuel oil and the combined amounts of unsaturated hydrocarbons are treated later in the process to produce higher boiling hydrocarbons.

All the gases and vapors from the conversion chamber are passed to a fractionating tower wherein a heavy condensate oil and a light condensate oil are separated from lighter vapors and gases. The heavy condensate oil may be used as feed stock for the gas generator or for the conversion chamber or may be further

5 treated in any desired manner. The light condensate oil may be further cracked by being passed through a separate conversion coil and then further treated to separate light hydrocarbon oils having the desired boiling range.

10 The gases and lighter vapors from the fractionating tower are treated in any suitable manner to separate normally gaseous unsaturated and saturated hydrocarbons as the C₂ to C₄ hydrocarbons, which can be liquefied fairly easily, from gases hard to liquefy such as methane, hydrogen, nitrogen, etc. The gases and vapors may be compressed, cooled and then passed to a separator for separating liquefied constituents containing C₂ to C₄ hydrocarbons from unliquefied constituents containing methane, hydrogen, nitrogen, etc. Other suitable methods for separation may be used. The liquefied normally gaseous hydrocarbons containing a relatively large proportion of unsaturated hydrocarbons are then passed through a conversion coil wherein they are heated to a conversion temperature to convert the gaseous constituents into higher boiling hydrocarbon oils suitable for use as motor fuel. The converted products leaving the conversion coil are preferably cooled and passed to a separator and further treated to separate light normally liquid hydrocarbons, such as motor fuels, from gases and vapors.

20 25 30 35 40 45 50 The drawing represents a diagrammatic flow sheet of apparatus suitable for carrying out my invention.

Referring now to the drawing, the reference character 10 designates a gas generator which is used to convert fuel oil or the like into gaseous products. Any suitable oil-gas generator which in operation produces relatively large quantities of unsaturated hydrocarbon gases may be used. Oil to be treated in the gas generator 10 is passed through line 12 by pump 14 and is mixed with a limited amount of air or suitable oxygen-containing gas to only partially burn the introduced oil. The air is introduced into the gas generator through line 16 by pump 18, and the mixture of oil and air, preferably in atomized form, is passed through line 20 to the bottom portion of the gas generator 10. The air is preferably preheated in any suitable manner before being mixed with the oil fed to the gas generator. An ignition opening 22 is provided for igniting the fuel and air in the gas generator 10.

As above described, an insufficient amount of air for complete combustion is mixed with the oil fed to the gas generator so that the oil

undergoes partial combustion and heat is generated to vaporize and crack the unburned portion of the oil. During this treatment a relatively large percentage of unsaturated hydrocarbons containing C₂ to C₄ hydrocarbons is produced. The hot gaseous products resulting from the partial combustion of the oil in the gas generator 10 together with inert constituents of the introduced air are passed through line 24 to a coking or conversion chamber 28 wherein they are intimately mixed with a relatively heavy high boiling residual oil or the like introduced into the coking chamber 28 through line 30 by pump 32.

The relatively heavy oil is heated to a conversion temperature by mixture with the hot gaseous products from the gas generator 10 and the heavy oil is converted into coke and gaseous products. During this coking treatment additional quantities of unsaturated hydrocarbons containing C₂ to C₄ hydrocarbons are formed. While my invention is particularly applicable to coking relatively heavy residual oils, lighter condensate oils may be cracked in the chamber 28, the heavy products unvaporized therein being withdrawn in any suitable manner as a liquid. The relatively large amount of unsaturated hydrocarbons formed in gas generator 10 and coking chamber 28 are further treated as will be described hereinafter to produce valuable motor fuels. While I have shown only one coking or conversion chamber in the drawing, it will be understood that a plurality of coking chambers may be used so that one may be cleaned out while another is in use. The coking chamber is provided with a manway 34 for the removal of coke or residual oil.

The hot vapors and gases from the coking chamber 28 preferably after suitable cooling to a temperature below cracking are passed through line 36 to the lower portion of a fractionating tower 38 wherein a relatively heavy condensate oil and a relatively light condensate oil are separated from gases and vapors which pass overhead from the fractionating tower 38. The heavy condensate oil is withdrawn through line 40 and may be burned in generator 10 or may be treated in any desired manner to produce additional cracking stock or other products. The light condensate oil collects on trap out tray 42 provided with a hood 44 in the fractionating tower 38. The light condensate oil is withdrawn from trap out tray 42 and preferably is passed through line 46 and conversion coil 48 by pump 50, wherein it is subjected to relatively high temperature and pressure conditions to effect the desired extent of conversion as will be later described in greater detail.

The vapors and gases which pass from the top of fractionating tower 38 are passed through line 52 and condenser 54 and then to a separator 56 for separating liquid gasoline constituents from normally gaseous hydrocarbons, hydrogen and nitrogen. The separator is provided with a valved liquid outlet 58 for withdrawing liquid constituents. The gases leave the top of the separator 56 through line 60, are compressed by a suitable compressor 62 and after suitable cooling in cooler 64 are introduced into a separator 66, which may be a fractionating column, for separating liquefied constituents from unliquefied constituents. The unliquefied constituents contain so-called permanent gases as nitrogen, hydrogen, methane, etc., which are with-

drawn from the system through valved outlet line 68.

The separated liquefied constituents comprise normally gaseous unsaturated and saturated hydrocarbons containing C₂ to C₄ hydrocarbons and are passed through line 70 by pump 72 to a conversion zone 74 wherein they are raised to a conversion temperature and maintained under such pressure to produce the desired extent of conversion into higher boiling hydrocarbons. Generally superatmospheric pressures are used. Instead of passing the gases from separator 56 to the compressor 62 and separator 66, they may be passed directly to the conversion zone 74 but I prefer to separate the permanent gases from the rest of the gases before treatment in conversion zone 74. Other methods of separation may be used, such as absorption followed by stripping the C₂ to C₄ hydrocarbons from the absorbent.

The converted products leaving the conversion zone 74 are passed through a cooler 76 or, if desired, are suitably quenched and then through line 80 into a high pressure separator 82 having a gas outlet 84 and a valved liquid outlet 86. In the separator 82, gaseous hydrocarbons and fixed or permanent gases are separated from liquid and liquefied gases. The liquid which contains gasoline constituents is withdrawn from the separator 82 through line 86 and may be further treated as desired to produce a suitable motor fuel having the desired boiling range. The separated gases are passed through line 84 to a high pressure fractionating tower 90 to separate C₂ to C₄ hydrocarbons from fixed or permanent gases such as methane and hydrogen which are withdrawn through valved line 92. The C₂ to C₄ hydrocarbons are suitable for reprocessing and are withdrawn from the bottom of the fractionating tower 90 and are forced through line 94 by pump 96 and is preferably recycled to the conversion zone 74 for further treatment.

The light condensate oil which collects on the trapout tray 42 in the fractionating tower 38 is preferably treated to produce lower boiling hydrocarbons and the description of this treatment will now be given. The light condensate oil is passed through conversion zone 48 wherein it is subjected to a relatively high temperature and maintained under superatmospheric pressure to effect the desired extent of conversion. The converted products leave the conversion zone through line 102 having a pressure reducing valve 104. A line 105 is preferably used through which a quench oil may be introduced into the conversion products leaving the conversion zone 48.

The converted products are then passed to a separating or evaporator zone 106 wherein liquid residue is separated from vapors, the liquid residue being withdrawn through line 108. The liquid residue may be used as charging stock for the conversion chamber 28. The vapors pass overhead through line 110 to a fractionating tower 112 which may be of bubble tower construction wherein they are fractionated to separate condensate oil from lighter hydrocarbon vapors. The condensate oil is withdrawn from the bottom of the fractionating tower 112 and passed through line 114 by pump 116 and is preferably recycled through the conversion zone 48 for further conversion thereof. The vapors remaining after fractionation leave the top of the fractionating tower 112 through line 120 and

are condensed by being passed through condenser 122, and then passed to a separator 124 wherein gases are separated from liquid. The liquid which contains hydrocarbon constituents suitable for use as a motor fuel is withdrawn through line 126. The gases leaving the top of the separator 124 may be passed to gas storage but are preferably passed through line 128 by pump 130 to line 60 for compression with the other gases prior to fractionation in separator 66 wherein hydrogen, methane and other diluents are separated prior to the conversion of the higher molecular weight gases.

A typical operation contemplated by my invention will now be given but it is to be understood that it is by way of example only and various changes and modifications may be made in the practice of my invention. The operating conditions may change, if necessary, when different oil stocks are used. The generator 10 is preheated to a temperature of about 1000° F. in any suitable manner before starting the operation of generating gas. An oil which can be vaporized without substantial decomposition to coke or tar and which has a gravity of about 30° to 33° A. P. I. is mixed with an insufficient amount of air to support complete combustion and the mixture is atomized and introduced into the preheated gas generator 10 wherein partial combustion of the oil takes place to produce hot gaseous products containing products of combustion, unsaturated hydrocarbon constituents, saturated hydrocarbon constituents, hydrogen, nitrogen, etc. The air is preferably preheated in any suitable manner to about 700° F. While I prefer to use an oil as described above, in some instances heavier oils may be used, relatively heavy distillates may be used, or a distillate stock may be used which is too refractory for cracking to gasoline. The gaseous products from the gas generator contain about 16% by volume of unsaturated hydrocarbons but with diluents such as hydrogen, methane and nitrogen removed from the gaseous products, the percentage by volume of the unsaturated hydrocarbons then becomes about 50%.

The products leaving the gas generator 10 after the partial combustion are at a temperature of about 1350 to 1575° F. depending on the ratio of air to oil, preferably about 1350° F., and they are introduced into the coking or conversion chamber 28 wherein they contact relatively heavy residual oil, preferably preheated, introduced into the coking chamber through line 30. The coking chamber is also preferably preheated to a coking temperature for the heavy oil when the operation is started. The heavy oil which is charged to the coking chamber may be a dirty residual oil. I am able to use cheap and dirty residual oils for the reason that the coking thereof is done in a separate chamber without interrupting the operation of the process.

Due to the high temperature of the products introduced into the coking chamber 28, the heavy oil is heated to a cracking temperature and cracked to produce gases and vapors and coke, the coke collecting in the coking chamber 28. The coking chamber is preferably maintained under atmospheric pressure or slightly greater than atmospheric pressure up to about 60 pounds per square inch. The heavy oil undergoing cracking in the coking chamber is maintained at a temperature of about 830 to 975° F. During the coking operation additional quantities of unsaturated hydrocarbons are formed in the coking

chamber to increase the total unsaturated hydrocarbons in the products of conversion.

The vapors and gases leaving the coking chamber 28 are passed to the fractionating tower 38 to separate heavy condensate oil and light condensate oil from gases and vapors which pass overhead from the fractionating tower 38. These gases and vapors contain the so-called permanent gases and also unsaturated hydrocarbon gases formed in the partial combustion of the fuel oil in the gas generator and also during the coking of the heavy oil in the coking chamber 28. These last-mentioned gases and vapors are treated in any suitable manner to separate the so-called permanent gases such as hydrogen, nitrogen, methane, etc., from the normally gaseous hydrocarbon constituents. The normally gaseous constituents containing unsaturated and saturated hydrocarbons including C₂ to C₄ hydrocarbons are then passed through the conversion zone 74 wherein they are maintained under suitable temperature and pressure conditions with or without the aid of catalyst to produce the desired conversion thereof into higher boiling liquid hydrocarbons including gasoline constituents.

For example, the normally gaseous hydrocarbons including the unsaturated and saturated hydrocarbons may be heated to a temperature of about 750° to 1300° F. while under a pressure of about 400 to 3000 pounds per square inch to effect polymerization of the normally gaseous hydrocarbons into normally liquid hydrocarbons. Where a predominantly aromatic liquid product is desired, higher temperatures, lower pressures and a shorter time of reaction may be used, as for example, a temperature of about 1200°-1750° F., and a pressure from atmospheric to about 200 pounds per square inch. Lower temperatures of from 200 to 600° F. and pressures of from 200 to 1000 pounds per square inch may be employed when catalysts are used.

During the treatment in the conversion zone 74, the normally gaseous hydrocarbons are converted into higher boiling normally liquid hydrocarbons and the converted products are passed to the separator 82 to separate a liquid fraction containing gasoline constituents from gaseous constituents.

The light condensate oil withdrawn from the trapout tray 42 and passed through the conversion zone 48 is raised to a temperature of about 925 to 1100° F. and maintained under a super-atmospheric pressure of about 200 to 1000 pounds per square inch while it is being passed therethrough. The conversion products are passed to the separator 106 under lower pressure and the vapors separated therein are further fractionated in the fractionating tower 112 to separate lower boiling hydrocarbons which are withdrawn through line 126.

While I have given an example for practicing my invention, it is to be understood that this is by way of illustration only and various changes and modifications may be made where different stocks or different operating conditions are used without departing from the spirit of my invention.

I claim:

A process for treating hydrocarbons that comprises mixing a condensate oil with less than the total amount of oxygen-containing gas necessary for complete combustion so that the oil undergoes vaporization and partial combustion with conversion into lower boiling hydrocarbons containing unsaturated hydrocarbons, in-

troducing a residual charging stock into a single-pass cracking zone, directing the resultant hot products formed by the partial combustion of the condensate oil into said single-pass cracking zone in contact with the residual charging stock to thereby maintain it at a coking temperature and effect conversion into a coke residue and vapors and gases comprising additionally formed unsaturated hydrocarbons, fractionating said vapors and gases to form fractions comprising light distillate, higher boiling reflux condensate and a normally gaseous fraction including unsaturated hydrocarbons, passing said reflux condensate to a recycling cracking zone wherein it is subjected to cracking conditions of temperature and pressure to effect conversion into lower boiling hydrocarbons including additionally formed unsaturated hydrocarbons, separating the

5 resultant cracked products from the recycling cracking zone into residue and vapors and gases, fractionating the latter vapors and gases to form fractions comprising light distillate, higher boiling reflux condensate and a normally gaseous fraction including unsaturated hydrocarbons, directing the latter reflux condensate to said recycling cracking zone, combining said normally gaseous fractions and directing the mixture to a conversion zone wherein it is subjected to conversion conditions of temperature and pressure to effect conversion into higher boiling normally liquid hydrocarbons, fractionating the resultant products of conversion to separate out a fraction comprising unconverted normally gaseous hydrocarbons and directing the latter fraction to said conversion zone.

HAROLD V. ATWELL.
